DISPOSABLE TOOTH BRUSH

Lois C. Cutler, 216 Winding Way, Merion, Pa., and Estelle Manfred, 326 Derwyn Road, Drexel Hill, Pa.

Filed Oct. 13, 1965, Ser. No. 87,450

Term of patent 14 years

(Cl. D9—2)

FIG. 1

FIG. 2

FIG. 3

FIG. 4

FIG. 5

FIG. 6

FIG. 7

FIG. 8

FIGURE 1 is a right-side elevational view of a disposable tooth brush showing our novel design;

We claim:

The ornamental design for a disposable tooth brush, substantially as shown.
